UNITED STATES PATENT OFFICE.

ANDREW D. MORSE, OF SOUTH FRAMINGHAM, MASSACHUSETTS.

BELT-HOLE GUARD.

1,198,746.

Specification of Letters Patent. Patented Sept. 19, 1916.

Application filed July 7, 1915. Serial No. 38,559.

To all whom it may concern:

Be it known that I, ANDREW D. MORSE, a citizen of the United States, residing at South Framingham, in the county of Middlesex, State of Massachusetts, have invented a certain new and useful Improvement in Belt-Hole Guards, of which the following is a specification, reference being had therein to the accompanying drawings.

- 10 The invention is an improvement in the covers, casings, or curbs, known sometimes as belt-hole guards, which are applied to the floors of buildings in connection with holes through which driving belts or bands of machinery stretch from one story to another above or below, and which are designed to protect such holes and close them more or less completely while leaving passageway for the belts or bands.
- 20 The invention provides a belt-hole guard having one or two cover-portions relatively adjustable so as to enable the lips of the opening or mouth occupied by the belt or band to be spaced at the right distance apart.
- 25 The adjustability provides for locating either or both of the said lips as close as may be desired to the belt or band. It provides for enabling the position of the lips and opening or mouth to be varied to suit 30 that of the portion of belt or band which occupies the belt-hole.

A feature of the invention is a belt-hole guard composed of sheet-metal.

An illustrative embodiment of the invention, containing in one structure the features to which reference has just been made, is represented in the drawings, which is an isometric view of the said embodiment and portion of a belt or band *a* which stretches 40 through the guard.

The said embodiment consists of a belt-hole guard made of sheet-metal and comprising a foot or flange 1, a shell-like body 2, and opposite cover-portions 3, 3, the said 45 cover-portions having rolled lips 4, 4, at their free margins at opposite sides of the opening or mouth for the belt or band, and end-wings 5, 5, at their opposite ends. The foot or flange 1 extends around the base of 50 the shell-like body 2 and stands out therefrom, and is adapted to be placed upon or against the surface of the floor, wall, or casing in which is made the belt-hole that is to be covered and protected. The fastenings 55 by which the guard is fixed in place will en-

gage usually with the said foot or flange. The length of the shell-like body between its ends is suitable to accommodate the width of the belt or band with which the guard is used. The height to which the said body 60 extends above the foot or flange is sufficient to meet the general requirements, as for instance to prevent water or dirt upon the floor from entering the opening or mouth of the guard, as well as to prevent dirt from 65 being swept upon the top of the guard and into the said opening or mouth. The two sides of the body which are parallel with the transverse surfaces of the belt are at a suitable distance from each other to allow for a 70 reasonable range of variations in the position of the belt or band between them. The two cover-portions 3, 3, are connected with the upper portions of the said two sides of the body, and project inward therefrom toward each other, with their lips approached more or less closely to the surface of the belt or band *a* which stretches through the belt-hole and the body of the guard and through the mouth or passage between the 75 said lips. The lips are made rounded by rolling the margins of the cover-portions upon themselves so as to provide smooth surfaces for contact with the belt or band. Each cover-portion is provided with an end-wing 5 at each end thereof. Each end-wing 80 extends at an angle from the corresponding end of a cover-portion, close alongside an end-wall of the body, and overlapping said end-wall. The two end-wings at either end 85 of the body also overlap more or less with each other across the adjacent edge of the belt or band. They close the space above the tops of the ends of the body, at opposite 90 ends of the cover-portions. Being flexibly 95 combined with the body 2, the cover-portions may be adjusted by bending them so as to locate their lips and the opening or mouth between them in the desired position transversely with relation to the belt-hole, 100 so as thereby to suit the position of the belt or band *a* within the belt-hole; and, also, so as to vary the width of the opening or mouth between the said lips, as well as the closeness of approach of the lips to the 105 surfaces of the belt or band. The rounded lips obviate injury to the belt or band from contact of the latter with the lips. The mouth or opening may be made of a width just sufficient to provide for the traveling movement 110

of the belt or band. The end-wings 5, 5, close the guard at opposite ends of the body and cover-portions in all positions of adjustment of the cover-portions, by overlapping with the end-walls of the body and with each other. The flexibility of the cover-portions secures the same results as hinging, which is an equivalent mode of providing for the adjustments.

10. My belt-hole guard attains all the ends ordinarily required of belt-hole guards, and in addition secures results and has advantages of its own. Thus, in case of fire, it will prevent flames from going through the belt-hole, thereby eliminating the chief objection to belting machinery through the floors of buildings. The floor may be flooded, in case of fire or accident, to a depth of three inches or more, according to the height of the body 15 2, without water running through the belt-hole. Dirt, sawdust, tools, etc., are prevented from dropping through the belt-hole into the room below. Dust is prevented from being drawn through the belt-hole by a current of air caused by the belt. Oil, etc., thrown from the belt is caught, whereby neatness around the belt-holes is preserved. Heat is prevented from passing from a lower floor to an upper floor through the 20 belt-hole. The lips prevent the belt from twisting. The guard takes up very little room, and when made of sheet-metal is light in weight. The size of the mouth or opening for the belt can be changed while the 25 guard is in use. In case the guard is made of sheet-metal, if the guard is accidentally struck, it will not break as in the case of a cast-iron guard.

The construction and relative proportions 30 may be varied in practice. Guards embodying certain of the characteristics of the invention need not necessarily be made of sheet-metal. In some cases the desired relative adjustment and results may be secured 35 by adjustment of one cover-portion and its lip. When the guard is furnished with two flexible cover-portions of the construction herein illustrated, the said cover-portions are independently adjustable.

50. I claim as my invention:—

1. A belt-hole guard having cover-portions provided with lips and relatively adjustable transversely to enable said lips to be spaced at the right distance apart to give 55 an opening or mouth between them of the desired width for the belt or band occupying the said opening or mouth.

2. A belt-hole guard having cover-portions provided with lips and independently 60 adjustable toward and from each other to enable said lips to be located at the desired distance relative to each other and to the respective surfaces of the belt or band occupying the space between such lips.

65. 3. A belt-hole guard comprising a shell-

like body and a cover-portion which is flexibly combined with the said body and adapted to be adjusted to enable the width of the opening or mouth for the belt or band to be adjusted.

4. A belt-hole guard having lips which are adjustable transversely relative to the belt-hole to enable the position of the opening or mouth between them to be adjusted to that of the belt or band occupying the said opening or mouth.

5. A belt-hole guard comprising a shell-like body and opposite cover-portions which respectively are flexibly combined with the said body and adapted to be adjusted relative to each other to adjust the width and position of the mouth or opening to be adjusted.

6. A belt-hole guard comprising a shell-like body and a cover-portion which is flexibly combined with the said body and adapted to be adjusted to enable the width of the opening or mouth occupied by the belt or band to be adjusted, the said parts made of sheet-metal and integral with each other.

7. A belt-hole guard made of sheet-metal and comprising a shell-like body and opposite cover-portions which respectively are flexibly combined with the said body and adapted to be adjusted relative to each other to vary the width and position of the opening or mouth occupied by the belt or band.

8. A belt-hole guard having the lips at its opening or mouth for the belt or band formed of sheet-metal rolled upon itself to 100 provide rounded surfaces for contact with the belt or band.

9. A belt-hole guard made of sheet-metal and comprising a shell-like body and a cover-portion which is flexibly combined with the said body, adjustable to enable the width of the opening or mouth for the belt or band to be varied, and provided with a lip formed by rolling the margin of said cover-portion upon itself.

10. A belt-hole guard made of sheet-metal and comprising a shell-like body and opposite cover-portions flexibly combined with the said body and adjustable to adjust the mouth occupied by the belt or band, the said cover-portions having rounded lips formed by rolling the sheet-metal upon itself at the margins of the cover-portions.

11. A belt-hole guard comprising a shell-like body and a cover-portion which is flexibly combined with the said body and adjustable to adjust the mouth occupied by the belt or band, the said cover-portion having end-wings overlapping with the body to close the spaces at the ends of the latter.

12. A belt-hole guard comprising a shell-like body and opposite cover-portions flexibly combined with the said body and adjustable to adjust the mouth occupied by the belt or band, the said cover portions having

end-wings overlapping with the body to close the spaces at the ends of the latter.

13. A belt-hole guard comprising a shell-like body and opposite cover-portsions flexibly combined with the sides of said body and adjustable to adjust the mouth occupied by the belt or band, the said cover-portsions respectively having end-wings overlapping

with the body-ends and with each other and closing the spaces at the ends of the body. ¹⁰

In testimony whereof I affix my signature in presence of two witnesses.

ANDREW D. MORSE.
